UNITED STATES PATENT OFFICE

CHARLES BEEL MARGRAVE, OF LOS ANGELES, CALIFORNIA

GOLF-CLUB GRIP

Application filed December 3, 1928. Serial No. 323,344.

My invention is a golf club grip.

An object of my invention is the construction of a grip for golf clubs which will have a certain resiliency and also allow the shaft of 5 the club to have a slight rotatable action in regard to the ends holding the grip.

A more detailed object of my invention is the construction of a grip utilizing a helically coiled spring with a tight coil which is 10 self wound on the club in a helical manner, the spring being slightly stretched and secured firmly to the shank of the club. Over this layer of coiled wire I wind first a layer 15 of friction tape and then a layer of leather or other suitable material to be immediately gripped by the hand.

My invention is illustrated in the accompanying drawings, in which:

Figure 1 is a perspective view of a club 20 having my grip attached thereto;

Fig. 2 is a perspective view partly broken away, showing the manner of constructing the grip.

Referring to the drawings, the shank of 25 the club is designated generally by the numeral 11 and on this there is an inner binding 12 formed of a spring. This spring is made of an elongated helically coiled wire having a tight coil and this coiled wire is itself wound 30 on the shank of the club at the handle portion; the coils being positioned close together. One end of the spring wire is secured by a 35 rivet 13 to the shank and the other end by a rivet 14 to the end of the shank.

A layer of friction tape 15 is then wound 40 on the handle over the coiled spring, this being wound into a tight binding and on account of its stickiness adheres readily to the wire spring. An outer layer of leather or equivalent material 16 is then wound on the friction tape, this being illustrated as having 45 a helical winding and is secured at one end by a string 17 or the like and at the other end by another binding of string 18. The slight hump 19 indicates the termination of the wire 50 coil.

In the use of the club with my hand grip, the wire gives a certain softness to the grip as the individual coils may compress slightly 55 when tightly gripped by the hand. When

a golf ball is struck by the head of the club, it tends to twist the shank 11 and the coiled wire allows this slight twist to the stem giving a resilient action as regards the gripping by the hands. As the outer part of the 55 hand grip is held firmly in the hands the coiled spring reacts to return the shank 11 to its normal position. While this relative twisting action of the shank 11 and the coil 12 is small, it is perceptible when striking 60 a ball.

Various changes may be made in the principles of my invention without departing from the spirit thereof as set forth in the description, drawings and claims. 65

I claim:

1. In a device as described, a shank of a club, a helically coiled wire spring wound on the said shank and secured thereto forming a hand grip. 70

2. In a device as described, a shank of a club, a helically coiled spring of small diameter wound on the shank in a helical winding with the adjacent windings contacting one with the other, and means to attach the winding to the shank thereby forming a hand grip. 75

3. In a device as described, a shank for a club, a helically coiled wire spring wound in a helical manner on the said shank and secured thereto, and a soft covering over the 80 spring thereby giving a hand grip.

4. In a device as described, a shank of a club having a tightly coiled helical spring wound in a helical manner on the shank and secured thereto with adjacent windings in 85 close contact, a binding of friction tape over the spring and a binding of soft flexible material over the friction tape, thereby forming a hand grip.

In testimony whereof I have signed my 90 name to this specification.

C. B. MARGRAVE.
